UNITED STATES PATENT OFFICE.

JOSEPH M. TATMAN, OF TAFT, CALIFORNIA.

OIL-SEPARATOR.

1,240,099.

Specification of Letters Patent. Patented Sept. 11, 1917.

Application filed July 20, 1912. Serial No. 710,588.

To all whom it may concern:

Be it known that I, JOSEPH M. TATMAN, a citizen of the United States of America, residing at Taft, in the county of Kern and State of California, have invented new and useful Improvements in Oil-Separators, of which the following is a specification.

This invention relates to improvements in oil separators, and has particular application to a device of this character for treating the product from oil wells, so as to separate the water from the oil.

Another object of the invention is to produce a separator wherein the water is separated from the oil where the product comes from the well in an emulsified condition, but does not remove the lighter constituents from the crude oil.

With the above and other objects in view the invention consists of the following novel combination and arrangement of parts hereinafter more fully described, illustrated in the accompanying drawings and pointed out in the appended claim.

25 In the drawings:—

The figure represents a diagrammatic view of the apparatus.

Referring in detail to the construction of the apparatus, the numeral 1 designates a suitable form of heating coil designed to contain a suitable quantity of heating fluid, such for example, as water, although any other fluid may be utilized and adapted to be placed in a suitable form of furnace (not shown) in proximity to the burning fluid therein, whereby the fluid in the heating coil may be heated to the desired temperature usually 212° Fahrenheit, although this temperature may be varied in accordance 40 with the requirements of any particular case. The coil, in the present instance, terminates in two parallel limbs 2, suitably spaced apart and each having the free extremity thereof equipped with a coupling 3.

45 Mounted within the coil 1 and preferably centrally thereof, is a second coil 4 adapted to receive the oil to be treated and extending outwardly of the coil 1 by way of the couplings 3 and through suitable stuffing boxes 5 are extensions 6. One of these extensions communicates with an oil tank or holder 7, which, contains the oil to be treated, while the opposite extension is in communication with a receiver 9, this extension being indicated at 8. The receiver 9 receives the oil subsequent to the passage thereof through

the inner coil and after being heated to the desired temperature.

Leading from the couplings 3 and in communication with the coil 1 are conducting pipes or conduits 11, arranged in open communication with the tank 12, which is designed to contain the heating fluid. One of the pipes or conduits 11 has communication with the bottom of the tank, while the other pipe communicates with the top thereof, so that the fluid within the tank may flow through the heating coil and back into the tank, the fluid being preferably under pressure from any suitable source to facilitate the circulation. The tank 12 may be supported in any suitable manner or in any convenient location, and in the present instance is shown supported upon a column 13.

50 In order to effectively heat the fluid flowing through the heating coil, without necessitating the heating the fluid contained within the tank 12, so that the separator may be brought into immediate use when desired and the heating fluid in the coil 4 heated to the desired temperature in a relatively short time, there is provided a by-pass 14, which, is preferably located between the conduits or pipes 11 in advance of the tank 12 and between such tank and the heating coil, 55 such by-pass enabling the fluid to circulate through the heating coil without reentering the tank. Thus, it will be seen that the fluid within the heating coil may be initially heated in a relatively short time and without the necessity of heating the fluid in the tank 12; furthermore, it will be noted that any loss of the fluid circulating through the heating coil due to vaporization will be immediately taken up owing to the tank 12 60 being in communication with the heating coil independently of the by-pass. However, a certain per cent. of the fluid in the coil will be forced back into the tank by way of the pipe 11' communicating with the tank at the upper end thereof, so that the water or other fluid within the tank will be maintained warm in the continued operation of the separator, thereby, eliminating chilling of the fluid within the heating coil 65 when the tank feeds such coil to take up any loss therein.

70 From the foregoing description it is believed that the construction, operation and advantages of the invention will be apparent. It is to be noted that the apparatus heats the oil within a closed pipe, thus

eliminating bubbling and waste incident thereto and the separator may be put into service and the fluid within the heating coil heated to the desired temperature in a relatively short period of time.

Having described the invention, what is claimed, is;

An apparatus of the class described comprising an oil circulating coil, a heating coil 10 inclosing the said oil circulating coil, a water tank arranged above the heating coil, said heating coil having its ends connected

respectively with the bottom and top portions of the tank and a by-pass establishing communication between the end portions of the coil, said by-pass being arranged in the coil at a point below the tank. 15

In testimony whereof I affix my signature in presence of two witnesses.

JOSEPH M. TATMAN.
